ATTORNEYS:

UNITED STATES PATENT OFFICE.

ALBERT G. SAART, OF ATTLEBORO, MASSACHUSETTS, ASSIGNOR TO THE
JAMES E. BLAKE COMPANY, OF SAME PLACE.

DESIGN FOR A HANDLE FOR BUTTON-HOOKS OR SIMILAR ARTICLES.

SPECIFICATION forming part of Design No. 34,644, dated June 11, 1901.

Application filed May 21, 1901. Serial No. 61,310. Term of patent 3½ years.

To all whom it may concern:

Be it known that I, ALBERT G. SAART, a citizen of the United States, residing at Attleboro, in the county of Bristol and State of Massachusetts, have invented and produced a new and original Design for the Handle of a Button-Hook or Similar Article, of which the following is a specification, reference being had to the accompanying drawings, forming part thereof.

Figure 1 is a side view of the handle, showing my new design. The handle is shown connected to a button-hook, the blade of a paper-cutter being indicated in broken lines. Fig. 2 is a transverse section of the same.

As shown in the drawings, the leading or material feature of my design consists of the raised scrolls *a*, terminating in an apex between curved bands, inclosing the spheroidal bosses *b*, above which the raised bands curve

in opposite directions under and then surround the panel *c*, terminating in the scrolled head *d*, ornamented with a shell ornament. In the panel *c* is the raised representation of a cupid. The ornamentations are in bold relief, as is indicated by the shading on Fig. 1 and the transverse section of Fig. 2.

Having thus described my invention, what I claim as new, and desire to secure by Letters Patent, is—

The design for a handle of a button-hook or similar article, as herein shown and described.

In testimony whereof I have signed my name to this specification in the presence of two subscribing witnesses.

ALBERT G. SAART.
